UNITED STATES PATENT OFFICE

155,934

DESIGN FOR AN EMBOSSED METAL SHEET

Richard S. Smith, Buffalo, N. Y.

Application April 16, 1949, Serial No. 2,037

Term of patent 14 years

(Cl. D54—2)

To all whom it may concern:

Be it known that I, Richard S. Smith, a citizen of the United States and resident of Buffalo, New York, have invented a new, original, and ornamental Design for Embossed Metal Sheet, of which the following is a specification, reference being had to the accompanying drawing, forming part thereof.

In the drawing:

Fig. 1 is a view looking directly at the face of an embossed metal sheet, showing my new design with the ornamentation omitted in part for convenience in illustration;

Fig. 2 is a cross-sectional view on the line 2—2 of Fig. 1; and

Fig. 3 is a cross-sectional view on the line 3—3 of Fig. 1.

I claim:

The ornamental design for an embossed metal sheet, as shown.

RICHARD S. SMITH.
